[57] CLAIM

The ornamental design for a powered pool cue chalker, substantially as shown.

DESCRIPTION

FIG. 1 is a front perspective view of a powered pool cue chalker showing my new ornamental design;

FIG. 2 is a rear side elevation view of the powered pool cue chalker of FIG. 1;

FIG. 3 is a left end view of the powered pool cue chalker of FIG. 1;

FIG. 4 is a bottom view of the powered pool cue chalker of FIG. 1; and

FIG. 5 is a right end view of the powered pool cue chalker of FIG. 1.
